J. C. FENNESSY
BASEBALL GAME APPARATUS

Filed March 16, 1927

UNITED STATES PATENT OFFICE.

JOHN C. FENNESSY, OF BROOKLYN, NEW YORK.

BASEBALL GAME APPARATUS.

Application filed March 16, 1927. Serial No. 175,844.

This invention relates to game devices and in particular to a base ball game device adapted to be operated by a number of players.

A particular object of the invention is to provide a base ball game device in which the ball may be pitched or projected in a variety of directions and thus provide a difficulty for the manipulator of the batting device.

A still further object of the invention is to provide a batting device in combination with a game of this character which may be operated transversely of the home plate and which may be released at the will of the operator to bat a projected ball.

A still further particular object of the invention is to provide movable wickets or like members which may be manipulated so that they will be placed in the path of the ball to constitute a "fly out".

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in perspective showing my game device laid out in the nature of a baseball diamond and a part thereof being broken away to show a movable wicket.

Figure 2 is an enlarged, sectional view taken on the line 2-2 of Figure 1 showing the ball projecting device.

Figure 3 is a sectional view taken on the line 3-3 of Figure 2 and shows the connection of the ball projecting lever with the revolving block in which they are held.

Figure 4 is a view in rear elevation of the ball batting device and strike marking boundary.

Figure 5 is an enlarged detail view in section, taken on the line 5-5 of Figure 4 showing the construction of the batting device and how the same is drawn up to its position preparatory to striking a projected ball.

Figure 6 is an enlarged view in perspective of one of the wickets used to catch a batted ball.

Referring to the drawings in detail, 5 indicates the box or frame which is provided with a baseboard 6, the same being slotted transversely, adjacent one end as at 7 to receive the upstanding wicket members 8, which are made from a piece of loop wire,

secured at its lower end in a slide 9 which is disposed in the groove 7 and is provided with a projecting handle portion 10 having formed on the end thereof, a finger piece 11. 60 This projected portion 10 extends through a suitable slot in the end wall 12 of the box member 5 and the finger piece 11 is disposed exteriorly of the box end 12 whereby the wicket or loop 8, of which there are two, 65 may be operated transversely of the box to be placed in the path of a ball projected from the batting device, the wickets being of course, operated by the players of the game. 70

Below the slot 13 formed in the end wall 12 of the game receptacle, is a slot 14 through which projects the ball thrower rod 15, the inner end of which passes through a suitable bore 16 in a revolvably mounted holder 17, the rod 15 being provided with a suitable 75

opening 16 through which projects the lower end of the ball projecting lever 17, which is pivoted as at 18 in the holder 17 and extends above the baseboard 6, and being curved at its upper end as at 19 to form a ball seat, the ball 20 being projected thereby toward the home plate 21 when the rod 15 is pushed inwardly by pressure of the hand of the player on the hand piece 22 formed on the outer end of said rod 15. The holder 17 has secured to its upper end, a retaining plate 23, which keeps the holder suspended in a suitable opening 24 in the baseboard 6, the same being prevented from having upward movement by a flanged ring 25 secured there- 80

to adjacent the under side of the baseboard 6, as shown in Figure 3. Through the medium of this construction, the holder 17 is freely revolvably in the opening 24 in the baseboard and thus the projector 17 may be so manipulated as to throw the ball 20 in any desired direction toward the home plate 21. In order 85

that the projected ball may be struck, I have provided a striker 26, which consists of the post member 27, suitably positioned beside and adjacent the home plate 21. At the rear of the home plate 21, the baseboard is provided with pennant bearing staffs 28, which indicate the limit of the strike zone, it being, of course, understood when a ball is projected and not struck, but passes between the two pennants 28, that it is regarded as a strike. 95

The batting device further consists of the horizontal supporting rods 29 which are 110 carried by the standards 27 and carry the bat operating member 30, the same consist-

ing of a block-like member which is slidably held on the rods 29 and carries at its lower end, the staple 31 to which is pivotally secured the ball striking bat 32. This bat 32 is provided at its free end with a slot 33 into which engages a hook 34 carried by the revolvable rod 35, the hook carrying portion 36 being square and being suitably secured to the rod 35 so that the bat carrying member may be moved longitudinally of the rods 29 and a turning movement of the rod 35 through the medium of the hand piece 36 carried at the outer end thereof will result in the upward movement of the hook 34 to disengage the bat 32 so that the spring 37, positioned therebehind will cause a forward, swinging movement of the bat and a striking of the ball as in the regular game. The spring 37 may be of any desired shape but I prefer to make use of a piece of spring steel secured to the lower end of the bat holding member 30 in any suitable manner and so arranged that its free end engages the upper portion of the bat and causes quick throw thereof about its pivot point 31 to strike a ball rolled thereunder.

It is evident, therefore, that a ball projected from the ball projecting device may be struck at from various positions, depending upon the judgment of the player manipulating the ball striking device. The baseboard 6 may be covered with any suitable material, such as felt and may be ruled to provide a zone 38 in which, if a ball lands fairly, a first base hit is recorded. The zones 39, 40 and 41 give the player a second base, third base or home run hit, as the case may be, but if the opposite player or the one manipulating the ball throwing device and wickets 8 manages to place one of the wickets in the path of the batted ball and the ball passes therethrough into the gutter or trough 41^a, it is considered a caught fly and the batter is out.

On the baseboard may be laid out, in the usual manner, a baseball diamond, consisting of home plate, first, second and third base and also arranged to provide a foul line, as in the regular baseball field. In order to make the game more effective, I have provided metallic figures of players which may be positioned as in the regular baseball game and these figures may be used as base runners to advance from one base to another during the play and may be of various colors to represent two opposing teams.

As far as practicable, the general rules of baseball will be followed, such as three strikes out, four balls take base, batter hit by a pitched ball takes the base and the rest of the rules. I have promulgated special rules in connection with my game device so that if the ball crosses the line between the markers back of home plate, it is con-

sidered a strike. If the ball strikes one of the markers and does not cross the line, it is a wild pitch and the base runners may advance one base. If this occurs on the third strike, the batter is not out and takes first base. If a batted ball hits the ball outside the foul line, it is a foul regardless of where it may roll. An infield player or figure hit by a batted ball is equivalent to a fly out. To be caught by the outfielder, the ball must pass through the outfield loop or wicket.

If the ball travels down the field without interference and is caught by the outfielder, that is, the outfield wicket, the batter is out but the base runners may advance one base. If a ball rebounds from the wall and is caught by the outfielder, it is a single but the base runners may advance two bases. If the outfielder wicket fumbles the ball, that is, if the ball does not pass through the wicket, the zone in which the ball comes to rest will determine the number of bases allowed the batter. In all other cases, the base runners may advance as many bases as the batter is allowed.

It is evident, therefore, that in the playing of my improved baseball game, skill is not only required by the opposing players but accuracy, close attention and skillfulness must also be brought into play in order that the ball may be projected properly within the bounds of the pennants and the person manipulating the batting device must also be on the alert to strike the projected ball, which is governed by the opposite player. In this way, a number of players may form sides and may play the game substantially as it is played outdoors and may have all of the thrills and excitement as is attendant in the regular outdoor baseball game.

It is evident, also, that I have provided an interesting and amusing device which will not only properly teach the proper playing of the game but will also call for a higher degree of skill than has heretofore been necessary in the playing of such games.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. A baseball game device comprising a baseboard marked to represent a baseball diamond, a ball projector, a batting member, means operated by the players for manipulating the projector and batting de-

- 35
vices and manually operated wicket mem- bers, arranged to be moved transversely of said baseboard to be positioned in the path of a projected ball.
- 5 2. A baseball game device comprising a baseboard laid out to simulate a baseball diamond, a ball pitching lever in which the ball is seated and by which it may be projected through a trajectory, a ball batting device, movable transversely of the home plate and means for operating the batting device to strike at a pitched ball at any point in the transverse movement of said batting device.
- 10 3. A baseball game device comprising a baseboard laid out to simulate a baseball diamond, a revolvable ball pitching device, means for aiming the device toward the home plate, a bat, a bat holder movable 20 transversely of the home plate and means for operating the bat to strike downwardly at a pitched ball at any point in the trans- verse movement of said bat holder.
- 15 4. A baseball game device comprising a baseboard having a groove therein, laid out to simulate a baseball diamond, a revolvable ball pitching device means for aiming the device toward the home plate, a ball batting device movable transversely of home plate, 30 means for operating the batting device to strike at a pitched ball at any point in the transverse movement of said batting device and wicket members operable in said groove and arranged to be placed in the path of a projected ball.
- 35 5. A baseball game device comprising a baseboard having marked thereon, a baseball diamond and field zones to indicate the value given a projected ball, a standard adjacent the home plate, a plurality of rods therein, 40 a bat carrier slidable thereon, means for moving the carrier along the rods to place it in the path of a projected ball, a ball pro- jecting means, a bat releasing member oper- able by said carrier moving means and a 45 spring for imparting a striking movement to the bat when the same is released.
6. A baseball game device comprising a baseboard having marked thereon a baseball field and having an opening therein at the 50 pitcher's position, a holder, means for re- volvably retaining the holder in the opening, a ball projecting lever pivotally operable in said holder and an operating lever manipu- 55 lated from the exterior edge of, the base- board extending through said holder and arranged to revolve the holder and engage said ball projector whereby the ball can be thrown toward the home plate from any selected angle, and a plurality of wicket 60 members operable transversely of the base- board and arranged to be positioned so that a projected ball can pass therethrough.

In testimony whereof I affix my signature.

JOHN C. FENNESSY. [L.S.]
